[57] CLAIM

The ornamental design for an upright support for shelves or the like, as shown and described.

DESCRIPTION

FIG. 1 is a perspective view of an upright support for shelves or the like showing my new design;

FIG. 2 is a left side elevation view thereof;

FIG. 3 is a front elevation view thereof; the rear elevation view being a mirror image of FIG. 3;

FIG. 4 is a top plan view thereof;

FIG. 5 is a right elevation view thereof; and,

FIG. 6 is a bottom plan view thereof.
